DEVICE FOR HOLDING ARTICLES

Henry Bihler, Akron, Ohio

Application July 20, 1931, Serial No. 551,835

1 Claim. (Cl. 211—70)

This invention relates to devices for holding articles, and more especially it relates to devices for holding a plurality of articles for display, or for providing convenient access to all the articles.

5 The illustrative embodiment of the invention herein shown consists of a device for holding a plurality of pencils, and the device may be used as a desk fixture, or it may be used as a means for displaying pencils or pen holders for sale. It 10 will be understood that the invention is not limited to the holding of pencils but is adapted for holding a number of different articles of similar shape, such as penholders and cigars.

The chief objects of the invention are to provide for individually holding a plurality of articles; and to provide convenient access to all the articles. Other objects will be manifest.

Of the accompanying drawing:

Figure 1 is a side elevation of one embodiment 20 of the invention consisting of a device for holding pencils, and a plurality of pencils mounted therein;

Figure 2 is a section on the line 2—2 of Figure 1;

Figure 3 is a section on the line 3—3 of Figure 2.

25 Referring to Figures 1 to 3 of the drawing, 10 is a base plate of any suitable or appropriate material, 11, 11 are journal brackets or standards rising from opposite ends thereof, and 12 is a shaft journaled in the upper portion of said brackets.

30 Mounted in spaced apart relation upon the shaft 12 are two disc-like pencil-engaging structures generally designated 13, which structures are adapted to engage and hold pencils at two points, being positioned sufficiently close together to en-

35 gage relatively short pencils. The pencils are held in horizontal position, and the brackets 11 are positioned far enough apart to clear the ends of the longest pencils of standard length. The shaft 12 is rotatable to bring the respective pencils

40 mounted in the structures 13 into a position of easy accessibility, and preferably one end of the shaft 12 is extended beyond its journal and provided thereat with a knob 14 to facilitate manual turning of the shaft. The knob 14 may be formed

45 with a peripheral groove 15 to accommodate a suitable driving belt (not shown) by which the shaft 12 may be power driven as when the device is used for display purposes.

50 Each of the pencil engaging structures 13 comprises a disc 16 of flexible material such as rubber that has a circumferential series of recesses 17, 17 in its structure adjacent its outer periphery,

said recesses having access to the latter through respective slots 18 of narrower width than said recesses, the slots and recesses of one member 13 being aligned with those of the other member 13. The recesses 17 are adapted to receive and support pencils 19 by engaging the latter at two points, the pencils being inserted into the recesses by forcing them through the slots 18, the resilient character of the material constituting the disc 16 permitting sufficient flexure of the walls of the 10 slots to admit the pencils. The recesses 17 need not be the exact size of the pencils but may be somewhat smaller or larger. If smaller, the pencils will be securely gripped by the material; if larger, the restricted width of the slots 18 will 15 prevent the pencils from falling out.

Each disc 16 is provided, at least on one side, with a hub member 20 or rigid material to which it is secured, as by rivets 21, 21. The hub member 20 is provided with an axial boss 22 and formed 20 with an axial bore 22^a through which the shaft 12 extends, the hub being secured to the shaft by means of a pin 23 or any other suitable device. The hub member 20 extends nearly to the recesses 17 of the disc 16 so as to provide lateral support 25 for the body portion of the disc. If desired, the perimeter of the disc 16 may be formed with V-shaped notches 24, 24 between the slots 18 to supplement the resilience of the rubber in giving a yielding character to the walls of said slots. 30

The device is simple, handy, and efficient, and may be used for supporting a large number of different articles.

What is claimed is:

In a device for holding articles, the combination of a horizontal rotatable shaft, end supports in which said shaft is journaled, and a pair of spaced article supporting structures mounted upon said shaft, said structures comprising rubber that is formed with aligned article-receiving recesses and entrance slots of narrower width extending from a margin of said rubber structures to said recesses, said recesses being of smaller size than the articles whereby the latter are yieldingly gripped by the rubber at spaced points intermediate their ends so that longitudinal movement of the articles relatively of the article supporting structures is prevented, and cut-away portions between the article-receiving recesses to prevent buckling of the rubber structure when 50 adjacent recesses hold an article.

HENRY BIHLER.
